UNITED STATES PATENT OFFICE.

ELZY M. WOLFF, OF MANSFIELD, OHIO.

DESIGN FOR A MONUMENT.

SPECIFICATION forming part of Design No. 36,832, dated March 1, 1904.

Application filed January 30, 1903. Serial No. 141,214. Term of patent 12 years.

To all whom it may concern:

Be it known that I, ELZY M. WOLFF, a citizen of the United States, residing at Mansfield, in the county of Richland and State of Ohio, have invented a new, original, and ornamental Design for a Monument, of which the following is a specification, reference being had to the accompanying drawing, forming part thereof.

The drawing is a front elevation showing the design of the monument.

What I claim as new, and desire to secure by Letters Patent, is—

The ornamental design for a monument, as shown.

ELZY M. WOLFF.
